(57) **CLAIM**

The ornamental design for a poultry feeder, as shown and described.

DESCRIPTION

FIG. 1 is right, front, bottom isometric view of a poultry feeder, showing my new design;

FIG. 2 is a top plan view thereof;

FIG. 3 is a bottom plan view thereof;

FIG. 4 is a left-side elevational view thereof;

FIG. 5 is a front elevational view thereof; and,

FIG. 6 is a rear elevational view thereof.

The dash-dash broken lines illustrate portions of the poultry feeder that form no part of the claimed design. The dash-dot-dot broken lines represent the bounds of the claim and form no part of the claimed design.

1 Claim, 6 Drawing Sheets
